ATTORNEY

UNITED STATES PATENT OFFICE.

ABRAHAM BEBEL, OF BROOKLYN, NEW YORK, ASSIGNOR TO THE DE LONG HOOK AND EYE COMPANY, OF PHILADELPHIA, PENNSYLVANIA, A CORPORATION OF PENNSYLVANIA.

EYE TAPE.

Application filed June 16, 1927. Serial No. 199,250.

My invention relates to the eye tape member of a hook and eye tape garment fastening device or structure and it has for its general object to provide a tape in which the fabric employed is relatively thin but in which the construction is such that relatively great strength and durability are obtained.

It also is an object of the invention to provide the eye tape of a hook and eye tape garment fastening device of a structure such that the opposite edges thereof consist of folded portions of material whereby a tape of smooth finish is produced.

Another object of the invention is to provide a tape comprising a plurality of strips on one of which the eye members of a hook and eye fastening device are mounted and the other of said strips constituting a means for covering the greater portion of said eyes and also constituting an element of the means for infolding an edge portion of a garment to which the said tape is secured.

Other objects and advantages of the invention will be apparent to those skilled in the art and either will be referred to in the detailed description of the invention which follows or will become apparent from such description.

In order that the invention may be readily understood and its practical advantages more readily and fully appreciated, reference should be had to the accompanying drawing in which I have illustrated an embodiment thereof in the form at present preferred.

In the said drawing:

Fig. 1 is a view in front elevation of a short section or length of one edge portion of a garment and of a corresponding portion of the eye tape embodying the invention;

Fig. 2 is a view in front elevation of a short section or portion of tape embodying the invention, one end portion of the cover strip or member of the tape being displaced in order that one of the eyes may be shown more clearly in elevation; and

Fig. 3 is a transverse sectional view taken on the line 3-3 of Fig. 1.

In the drawing I have shown, in Fig. 1, a section or portion 1 of a garment to which an eye tape of a hook and eye garment fastening tape is secured, a short section only

of the said tape being illustrated corresponding to the section or portion of the garment shown.

Broadly speaking, the tape comprises a main or body tape member 2 on which the loop eyes 3 are mounted at intervals and a cover strip or tape 4 by means of which the inner portions of the loop eyes are covered as is illustrated in the drawing.

In order that relatively thin fabric may be employed in the manufacture of the tape I prefer a structure such as is illustrated in the drawing in which a strip of fabric is folded as indicated at 5 along a line near one edge portion thereof so as to provide a portion 6 of double ply thickness to which the loop eyes 3 are secured. The loop eyes 3 preferably are of rectangular shape at their outer ends as indicated at 7 so that their opposite sides are in substantially parallel relation to each other. The inner ends of the opposite sides of the loop eyes terminate in fastening eyes 8 through which the tubular fastening projections 10 of the metal fastening devices 11 project. The said fastening projections extend through the double ply thickness of material 6 of the main tape member 2 as is clearly shown. The metal fastening devices 11 are of well known construction and are employed in the present construction for fastening the loop eyes to the tape in the usual manner.

The loop eyes having been secured to the double ply portion 6 of the tape structure as described, the strip of fabric of which the tape is constructed is folded along a line 12 near the middle of the width of the strip to provide an overlying portion 13 for covering the folded edge portion 14 produced as a result of the fold along the line 5 to which reference has been made previously. The outer edge portion of the part 13 is folded along a line 15 to provide an overlying portion 16, the edge of which terminates along a line adjoining the fastening eyes 8.

The loop eyes having been fastened to the double ply portion 6 of the strip of fabric and the latter having been folded in the manner as illustrated and as described, the cover strip 4 is then placed over the loop eyes, the outer edge thereof terminating or extending along a line adjoining the outer ends of the loop eyes 3. The outer edge por-

tion of the cover strip 4 is secured to the main tape 2 by means of a row of stitching 20. Because of the parallel relation of the opposite sides of the loop eyes 3 to each other the row of stitching 20 may be formed by a sewing machine provided with an attachment such as that disclosed in my application for Letters Patent of the United States filed November 15, 1926, Serial Number 10 148,413. The opposite or inner edge portion of the cover strip 4 overlies the portion of the main tape 2 inwardly of the loop eyes 3. In the securing of the eye tape to a garment an edge portion of the latter is inserted between the inner edge portions of the main tape 2 and the cover tape 4, as is shown in Figs. 1 and 3 of the drawing, and the inner edges of the parts 2, 4 and the interposed edge portion of the garment 1 are then secured together by a row of stitching 21. In the construction shown only one row of stitching is employed but it will be understood that if preferred one or more additional rows of stitching may be used.

25 For the cover strip I prefer a construction such as is illustrated in which the opposite edge portions of a strip of relatively thin fabric are folded along lines as indicated at 23 and 24 so as to provide a cover strip 4 which practically is of double ply thickness. As a result of folding the strip of fabric to form the cover strip or tape 4 the opposite edges thereof present a smooth and slightly finish as is apparent.

30 It will be seen that by my invention I have provided a tape of extremely simple construction which provides convenient means by which the tape may be secured to an edge portion of a garment. It also will be seen that when the specific construction as illustrated is employed I am enabled to use strips of fabric which are relatively very thin without, however, sacrificing strength of structure. The construction embodying 35 my invention as illustrated provides a tape which is flexible or pliable and which also is less bulky in proportion to strength of structure than tapes heretofore constructed and placed on the market.

40 Having thus described my invention, what I claim and desire to secure by Letters Patent is:

45 1. The eye tape of a hook and eye tape structure comprising a strip of relatively thin fabric, one edge portion of which is folded to form a part of double ply thickness, loop eyes secured to the said last mentioned part and the said strip folded along a line about the middle of its width to provide a portion which overlies the fold forming the said double ply part, the inner edge portion of the said last mentioned portion being folded over the inner edge of the said double ply part and terminating along a line in adjoining relation to the inner ends of the 50 said loop eyes, and a cover strip overlying the inner portions of the said loop eyes, and a row of stitching for fastening the outer edge of said cover strip to the said first named strip, the said latter strip being 55 folded as described.

50 2. The eye tape of a hook and eye tape structure comprising a main tape and a cover tape, the said main tape consisting of a strip of relatively thin fabric, one edge portion of which is folded to form a part of double ply thickness, loop eyes located at intervals on the said main tape, means for fastening the said loop eyes to the said part of double ply thickness, and the said strip being folded along a line extending longitudinally thereof to provide a part overlying the first named folded edge portion and the inner edge of the said last named part being folded inwardly and over the first 60 named fold, the edge thereof terminating along a line adjacent the inner ends of the said loop eyes, and the said cover tape consisting of a strip of relatively thin material, the opposite edge portions of which are 65 folded, a row of stitching for fastening the outer edge of the said cover tape to the said main tape, the said row of stitching engaging the opposite sides of the said loop eyes to form supplemental means for fastening them to the said main tape, and a row of 70 stitching for fastening the inner edges of the main and cover tapes together, the said last mentioned row of stitching operating to secure the said tape to the edge portion of 75 the garment which is infolded by the said inner edge portions of the said main and cover tapes.

75 In testimony that I claim the foregoing as my invention I have hereunto signed my 80 name this 13th day of June, A. D. 1927.

ABRAHAM BEBEL.
